DESIGN FOR A COMBINED BANK VAULT DOOR AND FRAME

William E. Adams, Hamilton, Ohio, assignor to
Herring-Hall-Marvin Safe Company, Hamil-
ton, Ohio, a corporation of New York

Application September 6, 1945, Serial No. 121,896

Term of patent 14 years

(Cl. D69—1)

To all whom it may concern:

Be it known that I, William E. Adams, a citizen of the United States, residing at Hamilton, county of Butler, State of Ohio, have invented a new, original, and ornamental Design for Combined Bank Vault Door and Frame, of which the following is a specification, reference being had to the accompanying drawing, forming part thereof.

Figure 1 is a front elevational view of a combined bank vault door and frame showing my new design.

Figure 2 is a view in perspective showing the frame and vertical edge and rear face of the door,

Figure 3 is a diagrammatic view showing the cross sectional configuration of the door.

Figure 4 is a side edge view of Figure 1.

I claim:

The ornamental design for a combined bank vault door and frame, as shown.
